UNITED STATES PATENT OFFICE.

FRANK L. BUFF, OF WICHITA, KANSAS.

SAFETY CONTROL VALVE.

Application filed June 8, 1926. Serial No. 114,511.

My invention relates to safety control valves, for use in connection with oil burning equipments, wherein the force of gravity or siphonage is employed in supplying the oil to the burner.

One object of my invention is to provide means whereby the gravity of siphon flow of oil will be automatically shut off at the source of supply in case of over feeding of the burner, or of an excess leakage of oil from burner supply pipe, such as would result from broken pipes, valves or connections.

Another object of my invention is to provide a device of the character described, which may be readily adjusted to meet the requirements of the various sizes and capacities of such oil burners as are now in general use for domestic and industrial heating.

With the foregoing and other objects in view, which will appear as the description proceeds, my invention resides in the combination and arrangement of parts, and in the details of construction hereinafter described and claimed, it being understood that changes in the precise embodiment of the invention herein disclosed may be made within the scope of what is claimed, without departing from the spirit of the invention.

30 Referring to the drawings:

Fig. 1 is a top view of my device, with part removed for convenience of illustration.

Fig. 2 is a side view of my device, with part removed for convenience of illustration.

35 Referring to the drawings in detail, reference character 1 designates the "cup-shaped" bottom section of a valve body, which is so formed as to constitute the bottom and side walls of a float chamber 13. The top section of valve body as shown at 2, forms the top covering of float chamber 13, and is so constituted as to accommodate the assembly of certain valves and connections, and contains a series of inter-communicating chambers and passage ways necessary to the proper operation of said device. The valve body sections 1 and 2 as shown, are joined at flange 27 by means of screws 25. The intake port 4 and discharge port 5 are tapped for standard iron pipe connections. A vent pipe 7 provides means for the admission of air into float chamber 13, which is necessary to the operation of float-valve 15. The air vent cock 6 provides means for exhausting the air from float chamber 13 when adjusting the device for operation, and when re-

adjusting same following an automatic "shut off" operation.

50 The float valve 15 being attached to float 3 as shown, is thereby raised and lowered in unison with said float, as in the presence or absence of fluid in float chamber 13. The float 3 is of the "air tight" sheet metal type, constructed of light gauge brass or copper sheet, and in general contour conforms closely to that of the float chamber 13 which incases it, due allowance being made in its dimensions to assure freedom from contact with side walls of the latter and to permit raising and lowering of said float. A center guide pin 24 depending from lower center of float 3, serves to secure the position of said float in proper alignment with float-valve port 12.

55 I install my device in the oil feed pipe leading from the supply tank to a burner, the burner supply pipe and tank not being shown, at or near said supply tank, connecting the pipe leading from the tank at intake port 4, and the burner supply pipe at discharge port 5. During normal operation, the oil enters intake chamber 8 at intake port 4, passes up through regulating valve port 9, thence through connecting passage-way 10 to float valve chamber 11 thence through float-valve port 12 to float chamber 13 and discharging at discharge port 5.

60 In adjusting for operation, I open the by-pass valve 17 which permits the flow of oil directly from intake chamber 8 to float chamber 13, and let it flow thus until feed pipes and valve chambers are fully charged with oil, as will be indicated by the rising of the oil in vent pipe 7 to a level with that of the oil in supply tank, and when thus charged I close by-pass valve 17 and open 65 regulating valve 16. I then start the burner in operation in the usual manner and adjust it to a maximum burning stage, and while thus operating I gradually close the regulating valve 16 to a point which permits the passage of less oil than that being consumed by the burner in maximum operation, as will be indicated by a receding of the oil at vent pipe 7, when I gradually open 70 regulating valve 16 until a flow of oil equaling that being thus consumed is permitted, as will be indicated by the oil in vent pipe 7 rising to, and resting at its proper working level, when no further care is required in 75 normal operation.

80 It will be observed that in normal opera-

tion float valve 15 is held in an open position by weight of fluid in float chamber 13 acting against float 3, and that said float chamber will remain thus charged with oil so long as the rate of oil flow permitted by regulating valve 16 is not exceeded by that withdrawn at discharge port 5, and that in case of over feeding of the burner, or of a leakage of oil from the burner feed pipe which would cause such excess discharge of oil, said float valve 15 will be closed by the lowering of float 3 to which it is attached, as a result of the exhaustion of oil from float chamber 13 through such excess discharge, and thus the oil supply is automatically shut off. The closing of float valve 15 causes the re-filling of float-valve chamber 11 and vent pipe 7 from the continued flow of oil through regulating valve 16 which continues until vent pipe 7 is filled to its working level, and thus it will be observed that such re-filling of valve chamber 11 and vent pipe 7 serves to effectively "seal off" the further inlet of air into float chamber 13, thus creating a vacuum which tends to prevent the further discharge of oil from the burner feed pipes.

After such automatic "shut off" operation as described, I proceed to readjust the control valve for operation as follows: I first open vent cock 6 to permit the escape of air from float chamber 13, then I re-fill said float chamber with oil by opening by-pass valve 17 and when oil appears at vent cock 6, I close it tightly and then close by-pass valve 17 so that the device is again ready for operation.

Having thus described my invention in detail, what I claim is new, and desire to secure by Letters Patent is:

40 1. In a safety control valve, a valve body comprising an intake port and a discharge port, each adapted for standard iron pipe connections, a vent pipe connection providing means for the intake of air, a vent cock connection providing means for the exhaustion of air, a screw-adjusting regulating valve interposed between said intake and discharge ports adapted to control the maximum flow of fluid to be permitted, a float-

actuated valve interposed between said regulating valve and discharge port operating to permit the free passage of fluid when the float is raised by the weight of the fluid present in the float chamber incasing it, and to automatically shut off the flow of fluid entirely when said float is lowered by exhaustion of fluid from said float chamber, as will be effected by a discharge of fluid at a rate in excess of that for which said regulating valve is adjusted, a by-pass valve controlling direct communication between the intake and discharge ports through said float chamber, providing means for adjusting said float-actuated valve in operating position.

2. In a safety control valve, a valve body comprising an intake port and a discharge port, each adapted for standard iron pipe connections, a vent pipe connection providing means for the intake of air, a vent cock connection providing means for the exhaustion of air, a regulating valve interposed between said intake and discharge ports adapted to control the maximum flow of fluid to be permitted, a float-actuated valve interposed between said regulating valve and said discharge port operating to permit the free passage of fluid at a rate of flow not exceeding that for which said regulating valve is adjusted, and to shut off the passage of fluid entirely when the rate of flow of fluid at discharge port exceeds that for which said regulating valve is adjusted, a float chamber interposed between said float-actuated valve and said discharge port serving to incase the float member of said float-actuated valve, means for supplying air to said float chamber, and means for exhausting air therefrom as necessary to the operation of said float member, a by-pass valve providing means for adjusting said float-actuated valve in operating position by the admission of fluid into said float chamber direct from the intake port chamber.

In testimony that I claim the foregoing as my own, I have hereto affixed my signature.

FRANK L. BUFF.
